CLAIM

The ornamental design for a turbo waste gate oil drain, as shown and described.

DESCRIPTION

FIG. 1 is a frontal perspective view showing front, top and right side of the turbo waste gate oil drain as it would be connected to a vehicle exhaust driven turbo charger system, showing my new design;

FIG. 2 is a left side elevation view thereof;

FIG. 3 is a right side elevation view thereof;

FIG. 4 is a rear elevation view thereof;

FIG. 5 is a front elevation view thereof;

FIG. 6 is a top plan view thereof; and,

FIG. 7 is a bottom plan view thereof.

FIG. 1

FIG. 2

FIG. 3

FIG. 4

FIG. 5

FIG. 6

FIG. 7
